METHOD OF AND MEANS FOR PRODUCING
BLANKS FOR ROLL THREADED BOLTS
AND THE LIKEWilliam L. Clouse, Tiffin, Ohio, assignor to The
National Machinery Company, Tiffin, Ohio

Application February 10, 1932. Serial No. 592,175

9. Claims. (Cl. 10—24)

This invention relates to a new and improved method of and means for producing blanks to be used in making roll threaded bolts and the like.

The roll threading of small size cold bolts is increasing in popularity as a manufacturing method the only difficulty being that roll threading tends to raise the top of the thread above the diameter of the shank of the bolt, which frequently is objectionable. Several methods are employed to 10 reduce the diameter of the shank previous to roll threading, so that the top of the thread will finally be equal in diameter to that of the shank. One method is to reduce the diameter by the extrusion process, which consists in pushing the blank 15 into the die having a shoulder and then a reduced diameter in the die block, so that in being forced down the hole in the die the stock must extrude or become reduced in diameter as it is passed back into the reduced portion of the hole 20 in the die.

The best means heretofore employed in the production of a blank having a shank with a portion of reduced diameter has involved the use of means for feeding the wire stock through a 25 shearing bushing and against a stop or gauge. A shear knife cuts off a suitable blank and carries it in front of the stationary die in which it is to be headed. The forward stroke of the heading tool first pushes the blank down the hole against 30 a backing pin, which is adjusted for the length desired on the shank of the bolt. When a portion of the shank is to be made of smaller diameter by extrusion, for purposes of roll threading, it is now customary to use a short heading die 35 corresponding in length to that portion of the bolt shank which one wishes to use, this being of the same diameter as the wire. Back of this die there is placed another die having a hole of reduced diameter to take care of the extrusion of 40 that portion of the shank which is to be roll threaded. In some cases the user bores back of the end of the heading die and inserts the extrusion bushing, in order to assist in maintaining alignment of the two dies. In any case, it is 45 very easy to adopt this plan on a solid die header. However, solid die headers are only satisfactory for making bolts of short lengths. Under actual manufacturing conditions it is not practical to head in a solid die a bolt the length 50 of the shank of which is more than five times its diameter. In other words, the maximum length of a $\frac{1}{2}$ " diameter bolt that can be successfully headed in a solid die is $2\frac{1}{2}$ ". Consequently, when the manufacturer wished to make bolts exceeding 55 this length, he has been compelled to try the

use of open die headers, and then he has run into complications which have made it impractical to extrude the end of the bolt shank. One reason for this is the fact that it has not been practical to split the extrusion bushing and make it integral with the gripping dies because even the finest crack would cause an objectionable seam on the extruded or reduced portion of the shank which would spoil any thread produced by rolling.

Where any effort has been made to locate the solid extrusion bushing in a backing block, it has been practically impossible to prevent one portion of the gripping die from springing back when the toggle pressure was relieved. While the toggle pressure is exerted upon the dies and the wire 60 is being pushed back thru the dies, it is at that time that the extrusion bushing must be perfectly centered with the split gripping dies. Enormous pressures are required to hold these dies closed, and where a number of joints are to be found back 65 of the dies and the usual spring is produced in the bed frame, there would be a tendency, when the toggle mechanism opens, for the gripping die on one side to move slightly with the result that it would cramp the stock sufficiently to prevent 70 the blank from being forced out of the extrusion die without being bent or otherwise spoiled. Consequently one of the essentials in any effort to use an extrusion die for receiving extruded metal is that this die must be definitely held in position 75 during the gripping portion of the cycle, but the pressure upon it must also be relieved at the time the gripping dies are opened, in order to overcome 80 the cramping tendency mentioned.

It is an object of the present invention to provide an extrusion die or bushing at the rear of cooperating gripping dies for the reception of metal extruded from a blank held by the gripping dies, means being provided for locating said bushing accurately with relation to the gripping dies, 85 thereby to prevent the formation of an extruded portion eccentric to the body of the shank of the bolt.

A further object is to subject both the bushing and the gripping dies simultaneously to the same high pressure gripping action and thereafter to simultaneously relieve these parts from pressure so that there will be no cramping of the blank between the bushing and the gripping jaws such as ordinarily results where one blank holding part 100 is relieved of pressure independently of other blank holding portions.

Another object is to insure accurate alignment of the several blank engaging and shaping portions during the extrusion operation.

110

With the foregoing and other objects in view which will appear as the description proceeds, the invention consists of certain novel features of construction and combinations of parts and 5 certain steps in the method hereinafter more fully described and pointed out in the claims.

In the accompanying drawings the preferred form of the invention has been shown.

In said drawings:

10 Figure 1 is a view partly in plan and partly in section of a portion of a header used in the formation of bolt blanks having reduced shank portions to be roll threaded.

Figure 2 is a section on line 2—2, Figure 1.

15 Figure 3 is a view similar to Figure 1 showing a modified construction.

Figure 4 is a section through the gripping dies spaced apart.

Figure 5 is a section through the extrusion die 20 or bushing.

Figure 6 is a plan view of a bolt blank produced by either of the mechanisms illustrated.

In the structure illustrated in Figure 1 there is shown a rigid structure such as a die block 1, 25 having a shear bushing 2 through which the wire stock S is fed intermittently in the usual way against a stop or gauge 3 and in the path of a shear 4. The reciprocating heading tool has been indicated at 5 and is to be actuated by any suitable mechanism.

30 In the block 1 is seated a stationary gripping die 6 and a movable gripping die 7 back of which is located a one-piece extrusion die or bushing 8 the bore or cavity 9 in which is coaxial with the cavity 10 between the dies 6 and 7 when they are closed together.

A gripping slide 11 is mounted in block 1 and carries die 7. This slide is adapted to be operated in properly timed relation with the tool 5 by 40 any suitable mechanism, such as the toggle set 12. When the slide is in one extreme position it thrusts with great force against bushing 8 and the meeting gripping dies, holding the bores or cavities 9 and 10 in accurate alignment.

45 An ejector pin 13 is movably mounted in cavity 9 and constitutes an abutment for the blank during the shaping operation, as is usual in metal working machines of this general type.

In practice the projecting length of stock S is 50 sheared off and carried to position between the cavity 10 and the tool 5. This tool advances to force the blank back into the cavity 10 which is approximately of the same diameter as the stock. During the shaping action of tool 5 the jaws 6 and 7 will be held together tightly by the toggle action and at the same time the bushing 8 will be subjected to the same pressure so that all of the dies 6, 7, and 8 will be thrust laterally in the same direction under the same pressure, thereby 55 equally compensating for any compression of materials and resiliency of the bed frame. Consequently the bores or cavities 9 and 10 will be held correctly aligned as the stock is pressed back into the dies.

60 Whether the machine be of the one-stroke, or of the two-stroke design, a portion of the metal of the stock will be extruded back into the cavity or bore 10 which is of less diameter than the stock, and that portion of the blank left outside of the dies will be shaped into the head of the bolt or other article being shaped.

Immediately following the formation of the blank and during the backward movement of the tool 5, the toggle set 12 acts to relieve pressure 75 on the dies, moving the die 7 the very slight dis-

tance from the die 6 necessary to eliminate the gripping action. As soon as pressure is thus released the die 6 has a tendency to shift slightly in the same direction as die 7, this being due either or both to resiliency in the bed frame and the block 1 and to the resiliency in the die.

80 Should the rear die or bushing 8 be held immovably back of the gripping dies, the slight relative movement of die 6 would tend to cramp or bind upon the shaped blank with the result that the blank could not be kicked out or ejected without injury thereto. In the present case, however, the bushing 8 is relieved from compression simultaneously with the gripping dies and, consequently, will tend to shift minutely with die 6 so that there will be no binding action on the blank and it can be ejected freely.

85 Instead of locating the extrusion die or bushing with all portions back of the gripping dies, a counterbore or recess 14 can be formed in the gripping dies 15 and 16 at the back end of cavity 17, as shown in Figures 3 and 4. This counterbore is adapted to receive one end of the die or bushing 18 formed in one piece and having a counterbore 19 at the front end of its cavity or bore 20. The diameter of this counterbore coincides with that of the bore or cavity 17.

90 The operation of the modified structure is the same as that previously described and positively prevents a binding action on or distortion of the blank.

95 The blank produced in both forms of machine has been shown in Figure 6 and includes the head 21, shank body 22 and reduced shank portion 23. This latter portion is adapted to be 100 threaded by the roll process, the metal displaced by the threading operation being forced outwardly so that the edges of the threads will be flush with the surface of the portion 22.

105 It is to be understood, of course, that bolts and other articles of different shapes, styles and sizes to be threaded by the roll method can be produced by the mechanism herein described and as separate gripping dies are employed, the article produced can be of any length desired.

110 What is claimed is:

1. Apparatus for producing a metal article having a shank with a portion reduced in diameter, including a rigid structure, a stationary die, an extrusion die or bushing at one end thereof, said dies bearing laterally against the structure, a movable gripping die, and means for exerting equal pressures against the gripping dies and the extrusion die to close the gripping dies and bind the stationary die and the extrusion die against 115 said structure, and for simultaneously relieving the dies of pressure, said dies providing coaxial cavities for the reception of stock, the cavity in the extrusion die being of less diameter than the cavity formed by the gripping dies.

120 2. Apparatus for producing a metal article having a shank with a portion reduced in diameter, including a one-piece extrusion die or bushing, stationary and movable gripping dies at one end thereof, there being coaxial, communicating stock receiving cavities in the dies, the cavity in the extrusion die being of less diameter than the cavity of the gripping dies, and means operating intermittently for simultaneously subjecting all of the dies to equal transverse pressure and for 125 simultaneously relieving all of the dies from pressure.

130 3. Apparatus for producing a metal article having a shank with a portion reduced in diameter, including a rigid structure, an extrusion die or 135

- 5 bushing having a side and an end thrust against said structure, stationary and movable gripping dies at one end of the extrusion die, said stationary die bearing laterally against said structure and backwardly against the extrusion die, there being coaxial bores in the dies, the bore in the extrusion die being of less diameter than the bore of the gripping dies, means for forcing stock longitudinally into the bores, and means 10 for exerting equal transverse pressure upon all of the dies during said forcing operation to close the gripping dies together and to bind the extrusion die and the stationary die against said rigid structure, said means being shiftable after said 15 forcing operation thereby to simultaneously relieve all of the dies from external pressure.
4. A means for shaping a blank and for releasing it without transverse binding thereon or distortion thereof, including relatively movable gripping dies having a stock receiving bore or cavity, an extrusion die at one end thereof having a bore of less diameter than that in the gripping dies, a rigid lateral backing for the extrusion die and one of the gripping dies, means for subjecting all of the dies to transverse pressure equally and simultaneously to bind the extrusion die and one of the gripping dies against said lateral backing and for simultaneously relieving the dies from transverse pressure, thereby to maintain the bores in axial alinement both while stock is being shaped therein under pressure and after the blank has been shaped prior to its ejection from the dies.
5. A means for shaping a blank and for releasing it without transverse binding thereon or distortion thereof, including an extrusion die, stationary and movable gripping dies, all of said dies providing alining bores, means for holding the extrusion and stationary dies against independent lateral movement in one direction, means movable with the movable die for subjecting all of the dies simultaneously to equal transverse pressures resisted by said holding means, and for simultaneously relieving all of the dies from all external pressures, thereby to maintain the bores in the dies in axial relation during the formation of a blank, and relieving the formed blank from unequal lateral pressures by the released dies.
6. In a metal forming machine, gripping dies, 30 a one-piece extrusion die at one end thereof, means for closing the gripping dies and subjecting all of the dies simultaneously to equal lateral pressure, a rigid means for resisting equally the pressures exerted through all of the dies, thereby to maintain the dies in correct working relation at all times while under pressure, said pressure exerting means being shiftable to relieve all of the dies from lateral pressure simultaneously thereby to maintain their correct axial relation after the forming operation and prevent unequal lateral pressures by the relieved dies upon the work.
7. In a metal forming machine, gripping dies, a one-piece extrusion die at one end thereof, means for closing the gripping dies and subjecting all of the dies simultaneously to equal lateral pressure, a rigid means for resisting equally the pressures exerted through all of the dies, thereby to maintain the dies in correct working relation at all times while under pressure, said pressure exerting means being shiftable to relieve all of the dies from lateral pressure simultaneously thereby to maintain their correct axial relation after the forming operation and prevent unequal lateral pressures by the relieved dies upon the work, and means for forcing a blank into the die cavities while the dies are under lateral pressure.
8. A machine for producing a metal shank having an extruded portion of reduced diameter, including an extrusion die, a die at one end thereof, said dies having communicating work shaping cavities in a predetermined relation, and means for subjecting the dies simultaneously to equal transverse pressures during the shaping operation and for simultaneously relieving said dies and the work therein from all transverse pressure, thereby to maintain accurately at all times the predetermined relation of the cavities.
9. The method of producing a metal shank having an extruded portion which consists in subjecting a shaping die and an extrusion die at one end thereof simultaneously to equal transverse pressures and thereafter simultaneously relieving the dies from all external pressure, whereby work shaping cavities in the dies which communicate solely at their ends will be maintained in a predetermined fixed relation during and subsequent to the exertion of pressure.
